UNITED STATES PATENT OFFICE.

DANIEL B. LUTEN, OF INDIANAPOLIS, INDIANA.

ARCH STRUCTURE.

No. 818,886.

Specification of Letters Patent.

Patented April 17, 1906.

Original application filed May 17, 1902, Serial No. 107,812. Divided and this application filed July 25, 1904. Serial No. 217,935.

To all whom it may concern:

Be it known that I, DANIEL B. LUTEN, a citizen of the United States, residing at Indianapolis, in the county of Marion and State of Indiana, have invented certain new and useful Improvements in Arch Structures, of which the following is a full, clear, concise, and exact description, reference being had to the accompanying drawings, forming a part of this specification.

This invention relates to improvements in arches of that class which are designed to serve as viaducts across streams, roadways, ravines, &c., and which are commonly constructed of concrete, stone, brick, cement, mortar, and other materials; and the invention has for its general object to provide an improved arch structure for this and analogous purposes characterized by greater strength and durability and capacity to resist the various strains to which the arch may be subjected, both by reason of the character of its environment and exigencies of travel thereover which might tend to disrupt or break the arch at various points, together with greater economy in respect to cost of materials and construction as compared with arches of this class at present in use.

To these and other minor ends my invention consists in an arch structure having the peculiarities of construction and advantages in use more particularly hereinafter described, and pointed out in the claims.

The present application constitutes a division of an application filed by me on the 17th day of May, 1902, Serial No. 107,812.

My invention relates chiefly to arches of concrete or other masonry which are reinforced with steel. In such arches economy of material may be secured by so proportioning the arch that certain portions will be in tension under applied loads and relying upon reinforcing tension-rods to resist the tensile stresses thus induced. At the present time steel is most frequently employed as a reinforcement for concrete in arches and analogous structures; but at present prices of these materials steel is more economical than concrete in tension, but not in compression. For maximum economy, therefore, the steel reinforcement should be designed as nearly as possible to resist the tensile stresses, relying upon the concrete to resist the compressive stresses. It is known that when one edge of an arch-rib is in tension at

any region the adjacent regions of the same edge will be in compression, while on the immediately opposite edge of the rib the reverse conditions will exist. In order, then, to pass through the portions in tension, the rods should pass from side to side of the rib, crossing the rib at points of change of stress. A reinforcing-rod, while not necessarily always in tension or in tension throughout, will approximate such conditions. Since the stresses in an arch structure may be to a certain extent indeterminate and since the loads may vary in their points of application, the points of location of these reinforcing-rods in the arch region are not always the same; but their location may be varied to suit the particular form or character of the rib and the given loadings. The desideratum is that the rods should pass through the regions properly in tension and to effect that pass from side to side of the rib. By combining series of rods having their points of crossing the rib angularly displaced with respect to one another in any method of alternation or succession an arch-rib may be built that will economically and efficiently support the great variety of loadings that may possibly come upon it.

Various arrangements of reinforcing tension-rods in connection with the same and different forms of arches are shown in the accompanying drawings, illustrative of my invention, wherein—

Figures 1, 2, 3, 4, and 5 are cross-sectional views, partially diagrammatic in character, of various forms of arches embodying my invention.

Referring to the drawings, Fig. 1 shows a low arch 10 of the semi-elliptical type resting upon abutments 11, embedded below and on either side of the bed of the stream, (indicated at 12.) Embedded in the material of the arch are several series of rods, the positions of each of the several series being indicated by the several lines therein shown as extending from side to side of the rib at various points. All of these rods are shown as occupying positions low at the crown of the arch and high at the haunches, but crossing the arch at various positions therein. The rods 13 of one series cross the rib on either side of and close to the center and pass along the outer faces of the rib and abutments and well down into the latter, as shown at 13^a. The rods 14 of a second series are extended close to the intrados of the crown for a greater distance

as to the points 14^a and thence across the rib and down along the outer face of the haunches and the abutments, as shown at 14^b. The rods 15 of a third series are extended close to the intrados of the crown practically for the entire extent of the latter to the points 15^a and thence are carried across the rib and abutments and down into the latter, as shown at 15^b. The arrangement of the series of rods 13 is for the purpose of sustaining the arch against a concentrated load applied directly on the crown, since the region near the center of the intrados of the crown is then in tension, as well as the region over the haunches. The second series of rods 14 are designed to resist the stresses of loads applied at or near the crown on each side of the center of the latter, in which case the tensional area at the crown is spread farther along. The described arrangement of the rods 15 reinforces the arch against vertical loads over the entire space, which would tend to cause tensional areas to the extent indicated. The extension of the lower ends of the several series of rods well down into the abutments serves to prevent overturning of the abutments under the thrust of the body of the arch against the abutments. As the thrust of the arch is transmitted to the abutments, these are tied together, preferably by one or more ties 16, embedded in the stream or its bed 12 below the water-line, these ties being anchored in the abutments in any desired manner. If they consist of rods, they may be anchored by bending their ends at an angle to their length, as shown at 16^a, or bending them around a T-rail, or in any desired manner.

In case of a semifluid condition of the earth upon and about the arch or under other conditions of loading it might occur that the pressure would tend to force the haunches in and the crown up. In this case the arrangement of the rods or other tension members would be high at the crown and low at the haunches, such an arrangement being illustrated in connection with the arch 17, (shown in Fig. 2,) wherein it will be seen that the respective rods of three series 18, 19, and 20 are all disposed high at the crown of the arch and extending for varying distances therealong and low at the haunches, crossing the rib at different points, and all of them being continued down the inner sides of the abutments, which regions are also in tension. With this combined arrangement the arch is well protected against pressure applied in the manner stated, as well as against the difficulty of accurately determining points of zero bending moment in the rib. As the abutments are pushed inwardly by the described force a pavement 21 of concrete or other suitable material is provided between the abutments to act as a strut and keep them apart. This pavement also serves as a

solid foundation for supporting the centering forms for the arch, a most important consideration, and also assists in a measure in supporting the arch through affording an increased bearing area.

Fig. 3 shows an arch 22 equipped with a combination of the series of tension members (illustrated, respectively, in Figs. 1 and 2) to guard against failure in tension due to both excessive loading on the arch and pressure against the abutments. In this figure the ties 16 are embedded in the pavement 21 and are thereby protected from rust and deterioration. The rods tie the abutments together and the pavement keeps them apart. The rods, moreover, strengthen the pavement and enable it to better stand the strains to which it is subjected in sustaining the forms for the arch in the course of its erection and the weight of the same after its construction.

Fig. 4 shows the same arch 22 having a similar arrangement of tension members to that shown in Fig. 3 and provided between its abutments with a pavement 23 in the form of an inverted arch, with the tension-rods 16 extending therethrough close to the intrados at the crown 24 and close to the extrados at the haunches 25, whereby it is supported by the rods 16 and forms a firm foundation for the arch carried above with an increased discharge capacity for the latter.

In an arch-rib supporting a skeleton superstructure, as all columns carrying a roadway, the region opposite the foot of each column will usually be a tensional region for a load applied over that column, so that tensional regions will usually occur along the intrados at the loaded columns and also along the extrados over the unloaded portion or portions. In such a structure, therefore, the tension-rods should alternate from side to side and with each other, so as to meet all possible conditions of loading. Such a situation is represented in Fig. 5, wherein 26 designates the arch rib or ring supporting a horizontal roadway 27 through a series of vertical columns 28, footed at intervals upon the upper surface of the rib. To reinforce the latter, I have represented three series of embedded tension-rods, of which one series 29 are disposed along the intrados at the crown for varying distances, then crossing the rib and extending the rest of the way close to the extrados. The rods 30 of another series lie close to the extrados for varying distances along the crown, then crossing the rib and hugging the intrados the remainder of the way, while still another series 31 are woven alternately back and forth, crossing the rib at several points. This weaving of different series of rods through the concrete from side to side of the rib not only reinforces the rib against tensile strains in the direction of its length, but bonds the material of the rib together securely crosswise, effectually prevent-

ing any tendency to splitting, which might be produced by excessive shearing or tensile strains or by lack of homogeneity of material.

I claim—

5 1. An arch having embedded therein a plurality of tension members passing alternately across the rib, said members being low at the crown and high at the haunches, and each of said members passing across the rib at different longitudinal points from the others, substantially as described.

15 2. An arch having embedded therein tension members passing alternately across the rib, said members being high at the crown and low at the haunches, substantially as described.

20 3. An arch having a plurality of tension members embedded therein; said members passing alternately across the rib and being high at the crown and low at the haunches, and each passing across the rib at a different point longitudinally from the others, substantially as described.

25 4. An arch having tension members embedded therein and passing alternately across the rib, some of said members being low at the crown and high at the haunches and others being high at the crown and low at the haunches, substantially as described.

30 5. An arch having two classes of tension members embedded therein and passing al-

ternately across the rib, one class being low at the crown and high at the haunches, the other high at the crown and low at the haunches, the several members of each class crossing the arch at longitudinally-different points from the others, substantially as described.

35 6. An arch having tension members embedded therein, some of said members being low at the crown and high at the haunches and others high at the crown and low at the haunches, a pavement extending across the bed of the stream between abutments or side walls, and ties embedded in said pavement and extending from abutment to abutment, substantially as described.

40 7. An arch having embedded therein rods, bars or other tension members in two or more series, following one face of the arch-rib, 50 thence across and following the other face of the rib, the points of crossing for the different series being angularly or laterally displaced with respect to each other, substantially as described.

55 Signed by me at Indianapolis, county of Marion, State of Indiana, in the presence of two witnesses.
